UNITED STATES PATENT OFFICE.

PAUL VIET, OF BILLANCOURT, FRANCE.

AUTOMATIC STARTING DEVICE FOR INTERNAL-COMBUSTION ENGINES.

Application filed February 6, 1926, Serial No. 86,640, and in France June 15, 1925.

My invention relates to an automatic starting device for internal combustion engines which is characterized by the fact that its several operative elements are grouped in a particular manner. The resulting apparatus essentially comprises a suction and discharge pump for gasoline or other liquid fuel which serves to facilitate the starting of internal combustion engines, as well as a device for the carburation of the air by the gasoline or like fuel whereby the engine may be started, the air to be carburetted being preliminarily compressed either by a hand or motor operated pump, or supplied from a compressed air tank.

My invention consists equally in the employment of two different pressures in place of one and of two spraying nozzles instead of one for effecting the formation and conveyance of the combustible mixture for the starting of internal combustion engines, the two pressures being utilized through the agency of a special device, as hereinafter more particularly described.

25 In the accompanying drawings:

The Figures 1 to 7 are diagrammatic sectional views of the operative elements of two embodiments of the invention.

Fig. 1 is a sectional view of a group of elements constituting an apparatus according to the invention.

Figs. 2, 3 and 4 are cross sections of the cock plug.

Figs. 5 and 6 are sectional views of a modified form of construction in which the several elements are differently disposed.

Fig. 7 is a sectional view of a modified form of the cock shown in Fig. 1.

Fig. 8 is a section of a complete apparatus according to the invention.

Figs. 9 and 10 are longitudinal sections of the plug keys of the valve.

Figs. 11, 11', 11'', 11³, 12, 12', 12'', 12³, 13, 13', 13² and 13³ are transverse sections of the valve shown in Fig. 8 taken along the lines a—a, b—b, c—c, c'—c'.

Referring to Figs. 1, 2, 3, 4, and 7, the apparatus comprises the hand-operated piston 1 withdrawing from the cylinder 2 the gasoline which is supplied through the inlet conduit 3 and discharging it through the outlet conduit 4 leading to the cylinders or the suction collector of the engine. The car-

bureter 5 is supplied from the cylinder 2, and the air thus carburetted proceeds directly to the engine valve gear through the outlet 6. Compressed air is supplied through the conduit 8, and can be brought to the upper part of the recipient 2, through the hand-operated valve 7. The whole apparatus is operated by combining the action of the compressed air controlled by the valve 7, and of the fuel feed pump, and of the cock plug 9, and three different positions are thus afforded for the fuel feed, as follows.

1: Withdrawal of the gasoline. 2: Discharge of the gasoline. 3: Carburation.

These operations are performed as follows:

For the fuel feed, the plug of the cock 9 is turned so as to connect the conduit 3 with the conduit 11 through the hole 10 (Fig. 3). By raising the piston 1 which is made tight by suitable packing, the gasoline will enter the cylinder 2.

The cock is then turned so as to connect 4 with 11 through the hole 14 of the cock plug (Fig. 4), and when the piston 1 is pressed down, the gasoline will be discharged into the engine. This can be carried out in one or more like operations, and finally the cylinder or recipient 2 is filled by raising the piston 1 to the maximum.

The operation of the cock may be simplified by placing a ball valve 10'', 14'' in the respective conduits 3 and 4 which will in this case be connected at the same time with the conduit 11 (Fig. 7).

For the carburation, the said cock is turned so as to connect the conduit 11 with the horizontal carbureter, and the conduit 12 with the valve 7, through the respective holes 15 and 16 of the cock 9 (Fig. 2).

By pressing upon the knob of the valve 7, the compressed air is admitted into the chamber 2 and presses upon the liquid, thus causing the latter to flow into the sprayer 5 of the carbureter, in which it is sprayed by means of a stream of air supplied through the conduit 13. This carburetted air is supplied to the engine, or to the valve gear, through the conduit 6. During this operation the piston 1 which is provided with a tapered internal head, will form a valve cooperating with a seat formed in the said chamber, and this arrangement, combined

with the packing, will make the device fluidtight under approved conditions, by the action of the pressure itself.

It will be noted that the said cock will afford three positions for the discharge, i. e., first for the supply of gasoline and air to the cylinder; second for the supply of gasoline and air to the admission conduits; third for the supply of gasoline to the admission conduits. Due to its functions, the said cock forms one of the features of the invention.

Figs. 5 and 6 show a modification of the apparatus shown in Fig. 1; herein the carbureter is vertical and the several parts are differently arranged, but the parts differ from those shown in Fig. 1 only by their relative disposition, and the same numerals are employed for similar parts, these being however shown as 5', 6' and the like.

20 The essential differences are as follows:

The cock is now perpendicular to the axis of the cylinder 2' instead of parallel thereto as in Fig. 1, so that the carbureter 5' will now be vertical instead of horizontal. The 25 valve device 7' remains parallel to the axis of the cylinder 2', but is now situated below the said cock instead of above it as in Fig. 1.

Since the functioning is quite the same as for the apparatus shown in Fig. 1 it will not 30 be necessary to further describe the several operations.

Obviously, the several elements of the carbureter such as the inlet and outlet for the carburetted air and the inlet for the compressed air may be given any suitable position, horizontal, vertical or oblique in the two apparatus above mentioned, without departing from the principle of the invention. In like manner I may provide for the supply 40 of compressed air and gasoline to the engine inlets by simply operating the hand-controlled valve.

Referring now to Figs. 8, 9 and 10 the apparatus comprises a piston 21, adapted to be 45 actuated manually in such a way as to suck into a chamber 22 the liquid fuel which it takes up at an admission conduit 23 and to force said liquid fuel by pressure through a tube 26 leading towards the cylinders or to 50 the suction collector of the engine to be started. A spraying nozzle 27 draws up the liquid fuel which passes then into a second spraying nozzle 28, then into an air conduit, whence it proceeds to the engine in the form 55 of carburetted air. A valve 24 is provided which renders it possible to put a conduit 31, connected to air reservoir of air under pressure into communication with the conduits 32 and 33. These conduits 32 and 33 are of 60 different cross sections and thus give rise to a difference of pressure between the low pressure air which comes through 32 around the spraying nozzle 28 and the high pressure air which comes through 33 around the spraying nozzle 27. Regulating screws 34 and 35

are also provided which render it possible to vary the magnitudes of the flow from the conduits 32 and 33 respectively.

The combined action of the pump piston 21 and of the distribution valves 24 and 25 70 renders it possible to carry out the following operations.

1. Suction of liquid fuel.

2. Forcing the liquid fuel by pressure into the admission conduits of the engine which 75 is to be started.

3. Production and compression of the carburetted mixture in the running position of the apparatus.

The said operations are carried out as follows:

a. *Suction.*—The plug key of the valve 25 is set in such manner as to establish communication between the orifice 23 and the conduits 29 and 30. The piston 21 is then 85 raised, thus causing the liquid fuel to be sucked into the chamber 22. The plug key of the valve is then turned in such manner as to establish communication between 26 and the conduits 29 and 30. The piston 21 90 is then depressed, whereby the liquid fuel is forced by pressure into 26 and from there into the cylinders of the engine which is to be started.

b. *Running position or carburation.*—The 95 preliminary operation is the filling of the chamber 22 which is effected in the manner which has just been described. The key of the valve 25 is then set in the position shown in Fig. 8, so as to establish communication 100 between the conduit 30 and the spraying nozzle 27. The plug key of the valve in its four positions as illustrated in the sections *a a*, *b b*, *c c* and *c' c'* renders it possible for the purpose of carburation to establish the communication of 31 with 32, 31 with 33 or 31 with 32 and 33 simultaneously. In the fourth position, viz., the stopping position, the communication of 31 with 32 and 33 is entirely 105 shut off, but these conduits are put in connection with the outer air in order to relieve the pressure in the interior of the apparatus entirely.

When the valve 24 is in the position in which 31 and 33 communicate, the air passes 115 in around the spraying nozzle 27 and acts on the level of the liquid fuel in the chamber through the medium of the conduit 36. The admission of the liquid fuel takes place at the exit of 27 through the air led in the 120 extension 37. The operation of the key 24 thus renders it possible to add to the action of the air arriving through 33 that of the air arriving through 32 and by making the discharge of air around the spraying nozzles 27 and 28 vary, it is also rendered possible to vary at will the richness of the carburetted mixture and its speed of admission to the motor. The regulating pins 34 and 35 serve 125 to effect this variation.

If desired the valve 25 may be omitted and replaced by ball valves. The conduits of the key 24 which serve to put the apparatus when in the stopping position into communication with the atmosphere, may likewise be omitted without detracting from the satisfactory working of the apparatus as a whole.

The arrangement described above are applicable to any relative position of the members of the apparatus, for instance they may be vertical, horizontal, or oblique, the annexed figures only showing one method of carrying the invention into effect. It is understood that variations of details may be made without departing from the scope of the invention. It may also be mentioned that the feeding of the chamber attached to the apparatus may be effected in the manner described by the aid of a little hand pump or in any other manner, even, for example, by gravity.

Claims:

1. A starting device for internal combustion engines comprising a fuel chamber, a piston in said fuel chamber, a fuel inlet, a conduit for compressed air, a carburetor, and a multiple orificed valve, said valve being adapted to provide communication between said chamber and said inlet when in

one position and when in another position to place said chamber in communication with said carburetor and said conduit.

2. A starting device as claimed in claim 1, in combination with a fuel outlet, said valve being adapted to place said chamber in communication with said outlet and simultaneously cut-off communication between the chamber and the inlet, carburetor and conduit.

3. A starting device as claimed in claim 1, in combination with a second conduit interposed between said carburetor and said first mentioned conduit to supply said carburetor with compressed air.

4. A starting device as claimed in claim 1, in combination with a second valve in said conduit for manually controlling the supply of compressed air to said multiple orificed valve.

5. A starting device as claimed in claim 1, said carburetor comprising two nozzles, one of said nozzles communicating with said chamber, the other of said nozzles communicating with said first nozzle and said compressed air conduit.

In testimony whereof I hereunto affix my signature.

PAUL VIET.
